Application August 19, 1930, Serial No. 476,422

4 Claims. (Cl. 179—170)

This invention relates to two-way transmission circuits, and more particularly to four-wire circuits and the arrangements often associated therewith for suppressing echoes.

5 For a discussion of some of the fundamental problems connected with the presence of echoes in two-way transmission circuits and for a description of echo-suppressing devices which are among those better known in the art, reference 10 may be had to an article by A. B. Clark and R. C. Mathes, Journal of the American Institute of Electrical Engineers, June 1925, pages 618—626.

In United States Patent No. 1,826,196, issued to L. G. Abraham October 6, 1931, there is disclosed the so-called "terminal echo suppressor," which accomplishes generally satisfactory suppression of echoes in long transmission circuits without the requirement of a "hangover" time of such length as to be undesirable.

20 In United States Patents Nos. 1,814,017 and 1,814,018, issued to S. B. Wright and D. Mitchell July 14, 1931, and in United States Patent No. 1,772,551 issued to D. Mitchell and H. C. Silent August 12, 1930, there is disclosed the so-called 25 "noise desensitizing echo suppressor," in which noise is rendered ineffective to operate the echo suppressor relays and yet the sensitivity of the device to voice currents remains unimpaired when no noise is present.

30 One of the objects of the present invention is to combine in a satisfactory echo suppressor arrangement the advantages of the "terminal" and the "noise desensitizing" suppressors.

A further object of this invention is to provide 35 an arrangement for suppressing echoes which is at once free from false operation and excessive "hangover" and sufficiently reliable to be satisfactory for use on transmission circuits having long four-wire sections.

40 These objects are attained by utilizing the "terminal echo suppressor" principle, employing one or more "noise desensitizing circuits" and employing a novel arrangement of relays and associated circuits, as will appear clearly from the 45 description of the apparatus and its operation found hereinbelow. This description is to be read with reference to the accompanying drawings.

Figure 1 of the drawings show diagrammatically, and in part schematically, one arrangement 50 of echo suppressor apparatus in accordance with the invention, while Fig. 2 shows in like manner a modification of the arrangement of Fig. 1 which may be preferable for some transmission circuits. The disclosure of Fig. 1, in addition to showing the 55 first arrangement, helps to bring out the purpose,

advantages and arrangement of the modified system of Fig. 2. Wherever such designation appears helpful to the reader of the diagrams, like reference characters are used in the two figures of the drawings to designate corresponding elements.

With reference to the details of the drawings, and first with particular reference to Fig. 1 thereof, there is shown a four-wire circuit having its upper two-wire path adapted for transmission from west to east, for instance, and its lower two-wire path adapted for transmission from east to west. At its west end the four-wire circuit is connected through the hybrid coil HC₁ to the two-wire line L₁, this line being balanced by the network N. At the east end the four-wire circuit is similarly connected through the coil HC'₁ to the two-wire line L₂, which is balanced by the network N'. It will be understood that the echo suppressing apparatus is located at or quite near the west end of the four-wire circuit in the one case, and at or near the east end of the four-wire circuit in the other case, and that the circuit may be very long, with no intermediate echo suppressing devices.

In the transmission line L there are disclosed two one-way amplifiers A₁ at the west end and A'₃ at the east end; likewise, in the line L' there are found the one-way amplifiers A'₁ at the east end and A₃ at the west end. It will be noted that on the output side of each of these four amplifiers there is an arrangement of resistances, which may be quite small, and repeating coils, and that the apparatus associated with these four amplifiers is also associated with the inputs of one-way amplifiers A₂, A'₄, A'₂ and A₄, respectively.

With reference to the above-identified disclosures of the terminal echo suppressor and the noise desensitizing echo suppressor, it will be seen that the arrangement of Fig. 1 of the present application combines the advantages of these two echo suppressing devices. When currents arrive at the west end of the circuit from the east end over line L', relay R₂ connected in the output of detector D₂ will operate to place a short circuit on the two-way line L unless earlier arriving currents flowing in the line L have broken the operating circuit through relay R₂ through the action of detector D₁ and relay R₁. Likewise, it will be seen that the desensitizing circuit S functions to prevent the operation of either the line shorting relay R₂ or the auxiliary control relay R₁ in response to noise currents in either side of the four-wire circuit.

At the east end of the four-wire circuit the

- echo suppressing apparatus is similar to that more fully disclosed in Fig. 1 as connected at the west end of the circuit. The detectors D'1 and D'2 corresponding to detectors D₁ and D₂ at 5 the opposite end, are shown only schematically, and, likewise, the desensitizing circuit S', schematically shown, will be understood to correspond to the desensitizing circuit S at the opposite end.
- 10 The most satisfactory understanding of the arrangement of Fig. 1 will be obtained, it is believed, from the following description of the operation of the circuits of that figure:
- Transmission from line L₁ at the west end of 15 the four-wire circuit to line L₂ at the east end, passes through the amplifier A₁ and on over the two-wire line L. At the output of amplifier A₁ a voltage drop is caused in the small resistances connected in the line. This potential is stepped 20 up through the repeating coils, is added to the voltage drop across the line, and is applied to the input of amplifier A₂. It will be understood that these transformer arrangements at the output of the line amplifiers are such that any transmission 25 passing into the lower branch of the four-wire circuit, due to slight unbalance through the hybrid coil H_{C1} will not affect amplifier A₄.
- From the output of amplifier A₂ the energy 30 passes into the detector D₁ and into the desensitizing circuit S through the hybrid coil H_{C2}. This coil, however, is so arranged that the output energy of amplifier A₂ cannot pass through the coil in any appreciable amount to affect detector D₂. Detector D₁ without the intervention of 35 the other elements would, of course, operate in response to either voice or noise energy of sufficient intensity passing through amplifier A₂ to actuate R₁. The winding W₁ of relay R₁ is included in the output circuit of detector D₁, and 40 if this winding is energized without the energization of either one of the other windings W₂ and W₃, the relay will operate to break the output circuit of detector D₂ through winding W₂ of relay R₁ and winding W₄, the operating winding 45 of relay R₂. Accordingly, given voice currents without considerable noise energy passing from west to east over line L, the disabling of the echo suppressor at the west end of the circuit is assured, and the talker connected with 50 line L₁ has proper control of the transmission circuit. It will be understood, of course, that if before the voice currents from L₁ reach amplifier A₁, voice currents passing in the opposite direction have reached amplifier A₃, detector D₂ 55 will have operated to energize winding W₄ of relay R₂, thus placing a short circuit on line L, and will have energized the winding W₂ of relay R₁ to bias this relay against operation by any current entering detector D₁.
- 60 If the energy passing through amplifier A₂ from the west end of the circuit or A₄ from the east end of the circuit is sustained noise, it causes the operation of the desensitized circuit S, described in some detail in the above-identified patent to 65 Mitchell and Silent. It will be sufficient to state here that this circuit comprises the vacuum tubes VT₁, VT₂, VT₃ and VT₄, the plate filament circuit of the last tube VT₄ including the biasing windings W₃ of relay R₁ and W₅ of relay R₂. The 70 condensers C and C₁ and the corresponding resistance arrangement r and r₁ operate in response to noise to cause an increased current flow in the output of tube VT₄, and the relays R₁ and R₂ are biased against operation by detector D₁ or 75 detector D₂, respectively. It will be understood

that if the energy is voice energy as distinguished from noise, the desensitizing circuit S operates in a manner to prevent the building up of a bias on the relays R₁ and R₂.

At the east end of the four-wire circuit the echo suppressor operation is quite similar to that described above in connection with the west end of the circuit. Voice currents arriving over line L and reaching the suppressor point before the arrival of voice currents from L₂, operate detector D'2, energize the operating winding W'4 of relay R'2 and the biasing winding W'2 of relay R'1, and, without opposition, short-circuit the line L' at the east end of the four-wire circuit. If voice currents from L₂ reach the suppressor point first, detector D'1 is operated, and the relay R'1 operates to break the circuit through relay R'2; thus control of the transmission circuit is assured to the talker connected with line L₂. Noise reaching the hybrid coil H_{C2} from either direction operates the desensitizing circuit S' to bias relays R'1 and R'2 against false operation.

Relay R₂ and relay R'2 should each have a small hangover time provided, corresponding to the time required for echoes to pass over short terminal circuits which may be connected to the four-wire circuit and which may be unequipped with echo suppressors. It is one of the chief advantages of the terminal echo suppressor arrangement, however, that such hangover time is very short in comparison with that heretofore required.

While the arrangement of Fig. 1 described above will in all probability meet the echo suppressing requirements of the greater number of circuits, there is the possibility that certain troubles in the operation of the suppressor apparatus will arise due largely to the fact that the control of the west suppressor, for instance, through the associated desensitizing circuit will be broken when noise is cut off by the operation of the suppressor relay at the east end. The desensitizing circuit during this quiet period will fall back to a condition in which no appreciable biasing current flows in the windings of the relays. Accordingly, when the short circuit is removed at the far end of the circuit and noise again comes on, the echo suppressing relay at the west end may be momentarily operated—before the desensitizing circuit has had a chance to build up again the biasing current in the relays, and the result will be a brief mutilation of speech. With this possibility of difficulty in mind, the applicants disclose in Fig. 2 of the drawings a modified arrangement which will remove the difficulty.

With particular reference to Fig. 2 of the drawings, at the west end of the four-wire circuit the transmission lines L₁, L and L', the hybrid coil H_{C1}, the balancing network N, the one-way amplifiers A₁, A₂, A₃ and A₄, and the transformer arrangements at the outputs of A₁ and A₃, are in arrangement identical with that shown in Fig. 1 and discussed hereinabove. It will readily be understood that at the east end of the four-wire circuit the arrangement of transmission lines and amplifiers and the arrangement of echo suppressor apparatus are similar to those disclosed in detail at the west end. Just as in Fig. 1, the two ends of the circuit correspond in these respects. Accordingly, the description of the arrangement and operation of the echo suppressor devices and circuits will, in general, be confined to the west end of the circuit without confusion to the reader.

It will be noted that in the arrangement of Fig. 2 there are two desensitizing circuits S₁ and S₂

- S₂, the former one being associated with the amplifiers A₂ and A₄ through the peculiar hybrid coil device HC₂. In addition there are employed a greater number of relays, with connections and 5 functions to be described hereinbelow. As indicated above, the main object of the modification of the circuit of Fig. 1 is to permit the desensitizing circuits at the west end of the four-wire circuit, for instance, to remain at a setting determined by the value of steady noise which has been arriving at this west terminal during a period when the transmission from the east end is cut off due to the echo suppressor action at the east end. In other words, when the noise comes 10 on again, the echo suppressor at the west end is found in the condition in which it was placed by the noise from the east end at the time of the break in the transmission, and so there is prevented the false operation of the west echo suppressor by a renewed transmission of noise. It will be noted that this is the only respect in which the action of the desensitizing circuit, as described above and in the patent to Mitchell and Silent, is changed or interfered with. 15
- In view of the discussion of the circuits of Fig. 1 given above, it is believed that the arrangement and action of the circuits of Fig. 2 will be readily understood from the following description of their operation: 20
- Transmission outgoing from the west terminal of the four-wire circuit passes through amplifier A₁, and energy is drawn off and passed through amplifier A₂ to detector D₁ and the upper desensitizing circuit S₁, it being understood that the hybrid coil HC₂ has the function of preventing energy coming to it from either direction from passing beyond it in any substantial amount. Thus, in the case now being considered, the lower desensitizing circuit S₂ and the detector D₂ are 25 unaffected.
- When detector D₁ operates, the operating winding W₁ of relay R₁ is energized. The energy passing into the desensitizing circuit S₁ has the action described above in connection with Fig. 1; 30 that is, if it is voice energy it has no appreciable effect on the relays, while if it is noise energy it operates to bias the relays against actuation. Let it be assumed for the moment that the energy passing through amplifier A₂ is largely speech 35 energy. Relay R₁ operates and closes a circuit through the winding of a relay R₅. This relay is given a suitable slow release time to prevent it from falling back between syllables. In the drawings this is shown accomplished by the action 40 of the condenser C₃ and the resistance r₃. The function of relay R₅ is to remove, and hold removed for the proper period, the ground connection of the circuit including the winding of the suppressor relay proper R₄, which, incidentally, is provided with a slow release time to take 45 care of delayed echo in circuits connected to L₁. The operation of relay R₅, in addition to removing ground from relay R₄, causes the discharge of a condenser C₄ and the consequent operation 50 of a relay R₆. This relay R₆ is given a slow release time which equals 2d, when d represents the time required for an echo to travel the length of the four-wire circuit plus the length of the connected two-wire line L₂ and any circuits connected thereto. The operation of relay R₆ removes one ground connection from the operating 55 circuits of relays R₇ and R₈ associated with the desensitizing circuits S₁ and S₂, respectively. It will be noted that, as discussed more fully 60 hereinbelow, a second ground is furnished for these relays R₇ and R₈ through the armature of relay R₃; relay R₆ in removing the ground through its armature provides for the release of relays R₇ and R₈ during the periods when noise energy from the east end of the circuit is cut off 65 by the echo suppressor operation at the east end, and the lower desensitizing circuit S₂ is consequently not receiving energy from the line L'. 70
- The relays R₇ and R₈ are arranged so that normally they are in operated condition and through their armatures provide for the normal connection of condensers C₁ and C₂ with the resistance arrangement r₁ and r₂ in the one case, and the normal connection of condensers C'₁ and C'₂ with resistances r'₁ and r'₂ in the case of the lower circuit. When, however, relays R₇ and R₈ are in any way released, these condensers are disconnected from their respective resistances, and, as will be understood by those skilled in the art, the voltages on the grids of the tubes VT₄ and VT'₄ 75 will be maintained at their last values. Accordingly, while these two relays are released no change of any appreciable amount can be made in the biasing current furnished by the two desensitizing circuits to the relays. 80
- It has been stated above that the operation of relay R₆ removes one ground from the operating circuits of relays R₇ and R₈, and that the other ground is furnished through the armature of relay R₃. Relay R₃ has two windings W₇ and W₆. Winding W₇ is included in the output circuit of tube VT'₄ of the lower desensitizing circuit and causes a bias to be applied to the relay which is normally not quite sufficient to release the armature and break the ground contact. 85
- Winding W₆ is included in the output circuit of the lower detector D₂ and is normally sufficiently energized to hold relay R₃ operated. It should be stated at this point that, preferably, provision is made for the operation of relay R₃ when no 90 noise whatever is present in the line L'; as will be understood by those skilled in the art, this bias may be provided by suitable voltage on the grid of the detector tube D₂, or by any other suitable means. 95
- Let it be assumed now that noise is coming over the line L' from the east end of the four-wire circuit. This noise energy passes through amplifier A₄ and enters both of the desensitizing circuits. Through the operation of the circuit S₁ a bias is built up in the winding W₃ of relay R₁ and winding W₅ of relay R₂. Likewise, through the operation of the circuit S₂ the biasing action described above is set up in windings W₇ of relay R₃. These noise currents, of course, 100 affect detector D₂ as well as the desensitizing circuits, and the current in winding W₆ of relay R₃ will be sufficient to hold that relay operated. The current in the other winding of the D₂ output circuit, W₄ of relay R₂, however, will 105 not be sufficient to cause the operation of that relay. When speech energy passing from west to east over line L reaches the east end of the four-wire circuit, the echo suppressing relay (corresponding to R₄) will disable the line L', and 110 the noise energy passing toward the west end of the four-wire circuit will be momentarily cut off. Relay R₆, however, has been operated as described above and is held in operated condition by the hangover action described above; accordingly, the right-hand ground for the operating circuits of relays R₇ and R₈ is removed. When the noise in line L' ceases, the current from detector D₂ will cease immediately. The current 115 from VT'₄ will not drop down so quickly, and 120
- 125
- 130
- 135
- 140
- 145
- 150

relay R_3 will then release removing the left-hand ground from the operating circuit of relays R_7 and R_8 , and these two relays release. The breaking of the contacts at their armatures disconnects the condensers and the resistances of the two desensitizing circuits S_1 and S_2 , and the proper bias is maintained from these circuits on relays R_1 , R_2 and R_3 . It will be understood that relays R_7 and R_8 release before the condensers C_1 and C_2 charge up to an appreciable extent, because the action of detector D_2 and relay R_3 takes place in a time which is short compared to the time required for the charging of condensers C_1 and C_2 .

15 From the above discussion, and from a consideration of the hangover time of relay R_6 , it will be understood that during a period of time equal to the longest quiet interval which can occur due to the suppression of noise by the speech 20 passing over line L , relays R_7 and R_8 will be released, and the proper bias to prevent subsequent false operation of the echo suppressor by noise will be maintained on the relays at the west end of the four-wire circuit.

25 It should be noted that if noise energy passes from west to east over line L , it cannot cause the release of relays R_7 and R_8 by itself, even though relay R_6 has operated to remove the right-hand ground from the operating circuits of 30 relays R_7 and R_8 : this is true because no substantial amount of this noise energy can pass the coil HC_2 and enter the lower desensitizing circuit S_2 to release relay R_3 and remove the left-hand ground. This point makes it clear why it 35 is desirable to use the two desensitizing circuits: if the circuit S_1 were made to perform the function of S_2 as well as its own, it would be possible for noise currents to build up a bias in the winding W_7 of relay R_3 which would cause the release 40 of that relay during the operation of relays R_1 , R_5 and R_6 . This would result in the release of relays R_7 and R_8 while relay R_6 was held operated by the noise currents in L , and the ground connection over the armature of relay R_5 would 45 be broken and the operation of the suppressor relay R_4 prevented in response to the voice currents in L' .

Furthermore, it should be noted that noise energy passing from east to west in line L' will 50 never cause the operation of relay R_1 because the hybrid coil HC_2 prevents this energy from entering the detector D_1 . Accordingly, even though relay R_3 is released because of the momentary decrease of noise, relays R_7 and R_8 will be held 55 operated through the released condition of relay R_6 (controlled by relay R_1 through relay R_5) which maintains the right-hand ground connection for relays R_7 and R_8 .

It remains to point out one other feature of the 60 arrangement shown in Fig. 2. If the four-wire circuit shown is connected through the two-wire circuits to other four-wire circuits, it may be necessary to make the slow release time of relay R_6 quite long—for instance, .5 second. In such a case 65 it may be desirable to provide for the cancellation of the slow release period of relay R_6 whenever the speech energy or the noise energy passing from east to west over line L' has an effect on the relays at the west end of the circuit which 70 is stronger than that due to the biasing current built up by the desensitizing circuits. This cancellation may be accomplished with the arrangement shown in the drawings, whereby an extra armature and an extra contact are added to relay

75 relay R_2 . When relay R_2 operates due to the conditions just discussed, this right-hand contact places a short circuit around the resistance r_4 forming a part of the slow release circuit of relay R_6 .

80 While the invention has been disclosed in two specific embodiments, the second being in the nature of a modification of the first, it is to be understood that such specific disclosure is not intended to limit the scope of the invention, which is 85 determined by the appended claims.

What is claimed is:

1. In a four-wire circuit including paths adapted for transmission in opposite directions, an echo suppressor relatively near each terminal of the four-wire circuit adapted to disable the outgoing path in response to voice currents in the incoming path, means responsive to noise currents for desensitizing said echo suppressor, and means responsive to the disabling of the incoming path by echo suppressor operation at the distant end thereof for maintaining on the near echo suppressor the desensitized effect produced by said desensitizing means.

2. In a four-wire circuit including paths adapted for transmission in opposite directions, echo apparatus comprising means for disabling the suppressing and associated apparatus relatively near each terminal of the four-wire circuit, said outgoing transmission path in response to voice currents in the incoming path, controlling means responsive to voice currents in the outgoing path for preventing the operation of said disabling means by voice currents in the incoming path of later arrival, means responsive to noise currents in either path for desensitizing said disabling means and said controlling means, and means responsive to the disabling of the incoming path by echo suppressor operation at the distant end thereof for maintaining on said disabling means 115 and said controlling means the desensitized effect produced by said desensitizing means.

3. In a four-wire circuit including paths adapted for transmission in opposite directions, the method of transmission control which consists in causing voice currents in the incoming path at either end of the circuit to disable the outgoing path at that end, provided said voice currents are of earlier arrival at that end than voice currents in the outgoing path at the same end, 125 causing noise currents in either path to set up a counter action to prevent false interruption of transmission, and maintaining the counteracting effect at either end of the circuit during a period when transmission is cut off at the distant end 130 thereof.

4. In a four-wire circuit including paths adapted for transmission in opposite directions, an echo suppressor relatively near each terminal of the four-wire circuit adapted to disable the outgoing path in response to voice currents in the incoming path, means responsive to noise currents for desensitizing said echo suppressor, means responsive to the disabling of the incoming path by echo suppressor operation at the distant end thereof 140 for maintaining on the near echo suppressor the desensitized effect produced by said desensitizing means, and means responsive to substantial increase of amplitude of the incoming currents for terminating the operation of said maintaining 145 means.
